Primary Examiner — Keli L Hill*Assistant Examiner* — Karra S Johnson(74) *Attorney, Agent, or Firm* — Morgan, Lewis & Bockius LLP(57) **CLAIM**

An ornamental design for a meatus measuring tool, as shown and described.

DESCRIPTION

FIG. 1 is a perspective view of my new design of a meatus measuring tool;

FIG. 2 is a top plan view of the design of FIG. 1;

FIG. 3 is a bottom plan view of the design of FIG. 1;

FIG. 4 is a first end view of the design of FIG. 1;

FIG. 5 is a second end view of the design of FIG. 1;

FIG. 6 is a right side view of the design of FIG. 1; and,

FIG. 7 is a left side view of the design of FIG. 1.

1 Claim, 4 Drawing Sheets
